UNITED STATES PATENT OFFICE.

JOHN J. HOPPES, OF SPRINGFIELD, OHIO, ASSIGNOR TO THE HOPPES MANUFACTURING COMPANY, OF SPRINGFIELD, OHIO, A CORPORATION OF OHIO.

WATER-DISTRIBUTER FOR FEED-WATER HEATERS.

1,096,508.

Specification of Letters Patent. Patented May 12, 1914.

Original application filed July 20, 1908. Serial No. 444,567. Divided and this application filed November 5, 1910. Serial No. 590,370.

To all whom it may concern:

Be it known that I, JOHN J. HOPPES, a citizen of the United States, residing at Springfield, in the county of Clark and State of Ohio, have invented certain new and useful Improvements in Water-Distributors for Feed-Water Heaters, of which the following is a specification.

This invention relates to improvements in feed water heaters and purifiers for steam boilers, and particularly to that class of feed water heaters in which water is fed to a series of pans and the exhaust steam is brought in direct contact with the water; this application being a division of my pending application Ser. No. 444,567, filed July 20th, 1908.

The object of my invention is to provide means for causing an even distribution of the feed water to the various tiers of pans or troughs of the heater.

The invention consists in the constructions and combinations of parts hereinafter described and set forth in the claims.

In the accompanying drawings Figure 1 is a side elevation partly broken away and shown in section, of a device embodying my invention. Fig. 2 is a detail in section of one of the branches of the supply pipe of the feed water. Fig. 3 is a detail of the regulating disk used in the branch connection.

Like parts are represented by similar characters of reference in the several views.

In the said drawings, a represents the shell or casing of the heater, which is preferably of cylindrical form and provided at one end with a fixed head a^1 and at the other end with a removable head a^2 in the usual manner. Located in the fixed head is an inlet a^3 for the exhaust steam from the boiler and at the top of the opposite end of the casing is an outlet a^4 for the exhaust steam.

The supply pipe, b , for the feed-water is provided in the usual way with inlet pipes, b^1 , to the heater, any number of which may be employed according to the number of tiers of pans or troughs used. Each inlet

pipe has branches, b^2 b^3 , located over the top pan or trough of each tier and adapted to discharge therein, these branches being connected to the inlet pipe by a T-connection b^4 . Located between the respective T-connections and the branches are removable disks b^5 having perforations b^6 .

In the installation of a feed-water heater and purifier it is necessary to employ a water supply pipe of a capacity sufficient to furnish a quantity of water to meet all the operating conditions, the size of this pipe being determined principally by the water pressure and the maximum amount of water required. Having determined the size of the supply pipe and knowing the minimum pressure of the water the T-connections and branches will be provided with disks having orifices of such capacity as will maintain an equal distribution of water to each series of pans; that is to say, the combined capacity of the orifices of the respective disks will be somewhat less than the capacity of the supply pipe so that a pressure of water will be maintained at all times within said pipe. This insures the water being carried to and distributed to the farthest tier of pans and the distribution to all of the tiers of pans will be uniform. Further, it will be seen that in any case where the conditions should change, such as a lessened pressure of water, these disks may be readily removed without changing the entire pipe system and new disks of lesser capacity inserted.

Having thus described my invention, I claim:

In a feed-water heater, a feed water pipe, a plurality of feed-water inlets from said pipe, said inlets having restricted openings of uniform capacity, the combined capacity of said openings being less than the capacity of said pipe, substantially as specified.

In testimony whereof, I have hereunto set my hand this 19th day of October 1910.

JOHN J. HOPPES.
